(57) **CLAIM**

The ornamental design for a display screen with animated computer icon, as shown and described.

DESCRIPTION

FIG. 1 is a front image of a display screen with animated computer icon showing our new design;

FIG. 2 is a second image thereof;

FIG. 3 is a third image thereof;

FIG. 4 is a fourth image thereof;

FIG. 5 is a fifth image thereof; and,

FIG. 6 is a sixth image thereof.

The appearance of the transitional image sequentially transitions between the images shown in FIGS. 1-6. The process or period that one image transitions to another image forms no part of the claimed design.

The outermost broken line perimeter showing the display screen is for the purpose of illustrating portions of the article and forms no part of the claimed design.
